UNITED STATES PATENT OFFICE.

CHANDLER KING, OF CHATTANOOGA, TENNESSEE.

DESIGN FOR A BOTTLE.

Application filed March 25, 1927. Serial No. 21,322. Term of patent 14 years.

To all whom it may concern:

Be it known that I, CHANDLER KING, a citizen of the United States, residing at Chattanooga, in the county of Hamilton and State of Tennessee, have invented a new, original, and ornamental Design for Bottles, of which the following is a specification.

The figure is an elevation view of a bottle, showing my new design.

I claim:

The ornamental design for a bottle, substantially as shown.

Signed at Chattanooga, in the county of Hamilton and State of Tennessee, this 18th day of March, 1927.

CHANDLER KING.
